(57) CLAIM

The ornamental design for a portable urinal, as shown and described.

DESCRIPTION

FIG. 1 is a perspective view of a portable urinal, showing my new design with a first lid in a raised position and a second lid in a closed position;

FIG. 2 is an exploded perspective view thereof, illustrated with the second lid moved away from the closed position;

FIG. 3 is a front elevational view of FIG. 1;

FIG. 4 is a rear elevational view of FIG. 1;

FIG. 5 is a right-side elevational view of FIG. 1, the left-side elevational view being a mirror image thereof;

FIG. 6 is a top plan view thereof; and,

FIG. 7 is a bottom plan view thereof.

The broken lines showing a female urinal adapter in the drawings depict portions of the portable urinal that form no part of the claimed design.
